COMBINED SISSY BAR PAD AND RECEPTACLE FOR CYCLES

Henry Akers and Patricia L. Akers, both of 271 Knox St.,
Costa Mesa, Calif. 92627

Original design application Oct. 1, 1969, Ser. No. 19,359,
now Patent No. 219,761. Divided and this application
Dec. 28, 1970, Ser. No. 26,677

Term of patent 14 years

Int. Cl. D12—16

U.S. Cl. D90—15

FIG. 1 is a front elevational view of a combined sissy bar pad and receptacle for cycles embodying our design;

FIG. 2 is a side elevational view, the opposite side being substantially a mirror image thereof;

FIG. 3 is a rear elevational view thereof;

FIG. 4 is a top plan view thereof; and

FIG. 5 is a bottom plan view thereof.

This application is a division of our application Ser. No. D. 19,359, filed Oct. 1, 1969, now Patent No. D. 219,761.

We claim:

The ornamental design for a combined sissy bar pad and receptacle for cycles, as shown and described.
